AUTOMOBILE TRUCK

John J. Powers, St. Louis, Mo.

Application December 16, 1948, Serial No. 150,197

Term of patent 14 years

(Cl. D14—3)

To all whom it may concern:

Be it known that I, John J. Powers, a citizen of the United States, residing at the city of St. Louis, State of Missouri, have invented a new, original, and ornamental Design for an Automobile Truck, of which the following is a specification, reference being made to the accompanying drawing, forming a part thereof, in which Figure 1 is a right-hand perspective view of an automobile truck embodying my new design; Figure 2 is a rear end perspective view thereof; Figure 3 is a left side perspective view thereof.

The characteristic features of my design reside in the portions shown by means of full lines in the drawing.

I claim:

The ornamental design for an automobile truck, substantially as shown and described.

JOHN J. POWERS.
